FRED S. PAYNE, OF BOSTON, MASSACHUSETTS, ASSIGNOR, BY MESNE ASSIGNMENTS, TO ELEVATOR SUPPLY & REPAIR COMPANY, OF CHICAGO, ILLINOIS, A CORPORATION OF ILLINOIS.

ELECTRIC SIGNALING DEVICE FOR ELEVATORS.

1,108,782.

Specification of Letters Patent.

Patented Aug. 25, 1914.

Application filed October 17, 1904. Serial No. 228,778.

To all whom it may concern:

Be it known that I, FRED S. PAYNE, a citizen of the United States, residing at Boston, in the county of Suffolk and State of Massachusetts, have invented certain new and useful Improvements in Electric Signaling Devices for Elevators, of which the following is a full, clear, and exact specification.

10 My invention relates to electric signaling devices for elevators, and my general object is to improve upon the constructions heretofore used, and particularly to improve upon the construction set forth in my prior patent #756,275.

One of several objects of my present invention is to provide a signaling system which is adapted for use with two or more elevators, whereby all cars going in the same direction may be signaled from a single push-button in conjunction with means for controlling the signals of the cars by means of suitable devices to be operated by the car operator, such, for example, as the floor gates or doors which are arranged along each elevator shaft at each floor.

Other objects of the invention will become more clearly apparent from a thorough understanding of the invention.

30 Another object of my invention is to provide an improved construction by which the device or mechanism which causes a signal or signals to be given or operable may be maintained in such signal-giving position and restored to normal condition.

In the drawings which show the preferred form of my invention, Figure 1 represents a side elevation; Fig. 2 an end elevation of the overhead mechanism for controlling the circuits; Fig. 3 is a diagram of connection for operating the signals in the cars; and Figs. 4 and 5 are detailed diagrams.

40 On the overhead of each elevator is provided the construction shown in Figs. 1 and 2, which may be used if desired. The gear 1 is driven from the overhead sheave of the elevator and meshes with the gear 2, which drives the worm shaft 3 mounted in the frame 4. The carriage 5 meshes with the worm 3 and is moved to the right or left by said worm, depending upon the direction of rotation or the direction of movement of the car. The carriage bears a brush 6, which

55 makes a connection with the contact plates 9, 10, 11, and with the switches 107, 108, and stops 7 are provided at each end of the worm. The operation of these parts and their connections need not be more specifically described because it forms no part 60 of the present invention.

The belt 13 transmits motion to a grooved barrel 16 mounted on the shaft 15, and meshing with the barrel is a gear 35 also carried on a worm shaft 33 so that it moves to the 65 left or right, depending on the direction of movement of the car. 34, 34 are suitable stops at the end of the same. The train of gears 36, 37, 18 transmits motion to a shifting switch which, in the present instance, is 70 illustrated for two floors only and comprises two levers 19 and 25 and suitable contact plates hereafter to be more specifically described.

75 31, 30, 29 is a suitable friction connection so that the switch will be thrown to the left from its position shown, until it abuts against a stop 39 when the car reverses its direction of movement. Such friction actuated shifting switches are so common in 80 this art that it is not considered necessary to more specifically describe the same, as no claim is herein made to the specific form of mechanism for accomplishing such shifting.

85 In the diagram of Fig. 3, A represents one car and B represents another car, which are supposed to be traveling in their respective shafts or wells and which pass the gates 40, 41 and 42, 43. The gates open in the direction of the arrows. Each of the cars is provided with electrically-operated signaling mechanisms for signaling the operator to stop at the floors, and such signaling mechanism is preferably an electric lamp, one 90 for each floor in each car. The lamp 44 in car A and 45 in car B being signals to stop at the fourth floor, and lamps 46 and 47 at the third floor. In the present instance only one lamp is used for each floor as this 95 is the preferable construction.

48, 49 represent devices to be operated by the intending passenger on the fourth floor when he desires to signal the car, and which I have generically termed "passenger's- 105 buttons", and 50, 51 are similar buttons for the third floor. The means for operating a

signal comprises one of these passengers'-buttons and mechanism corresponding to, and set by, each button, such, for example, as a normally-open switch which is closed to close the circuit through the signal lamp, preferably as soon as a push-button is operated. The specific mechanism above referred to as corresponding to, and set by, each button, preferably comprises a switch, such as indicated at 52 or 53, which may be closed by a reciprocating core 54 or 55 of a setting magnet. The normal circuit is indicated, for example, in Fig. 5. The circuit through lamp 44 is normally open at 52, and from the point 56 a branch circuit goes through the down "setting" magnet 57, through the uninsulated portion of the core 58 of the down restoring magnet 59, and by wire 60 to the normally-open passengers'-button 49, and from there to the stationary contact plate 22, and by switch arm 19 to the contact plate 20, and so to the other side of the source of electro-motive-force. This will energize the setting magnet 57, which will cause its core 54 to move up and close the circuit through the lamp 44. 61 is a conducting piece carried by the core 54 but insulated therefrom by insulating material 62. As the push-button 49 is usually sprung-pressed so as to open as soon as the intending passenger takes his finger off, it is desirable to provide a maintaining circuit which will keep the magnet 57 energized and the switch 52 closed. When the button is pushed the core moves from a normal position shown in Fig. 5 to the position of the same core 54 shown in Fig. 3, and a branch circuit from the magnet 57 is thus closed by way of wire 64, conducting piece 61, wires 65 and 66, which keep the magnet energized even though the passenger takes his finger off the push-button 49, and thus maintains the magnet circuit closed and the signal lamp lighted and gives a signal to the operator to stop at the floor to which that lamp corresponds. When the operator stops at a floor, he operates a switch to break the circuit of the setting magnet, which allows the core to drop and restore the circuits to their normal condition. I have shown at 67 such a normally-open switch in Fig. 5 which, when closed, closes a circuit which may be traced from said switch to the arm 19, stationary contact 68, through the down "restoring" magnet 59 and out by wire 66. This energizes the magnet, raises the core 58 until its insulated portion 69 breaks the circuit through the magnet 57, thus allowing the core of the setting magnet to drop and open the lamp circuit, and when the gate is again shut the switch 67 automatically opens the restoring magnet circuit and thus the parts are all restored to their normal condition. The down setting magnet 69 and down restoring magnet

70 have corresponding circuits so as to be controlled from the down button 51 to control the light 46, and the switch arm 25 for the third floor makes contact with a stationary plate 71 corresponding to the plate 70. The door switch 72 of gate 41 also controls the restoration in the same manner. In other words, when the car is moving down the shifting switch stands in the position shown at the upper left-hand portion of Fig. 3, and for each floor there is provided a stationary restoring contact 68 or 71 and a corresponding arm 19 or 25 in electrical contact therewith, and a common contact 20. When the car reverses its direction of movement the switch arms 19 and 25 are thrown forward to the opposite position, that is, to the position illustrated at the upper right-hand corner of Fig. 3, in which the arms 19 and 25 will contact with the stationary plates 73 and 74 and the upper end of the arm 19 with the plate 23, so that the "up" button will control the lights of that car which is moving up and the operation of the corresponding gates 21 will restore the circuits in a similar manner.

Referring to car B at the right, which is assumed to be going up and in which the "up" push-button 50 of the third floor has been operated so that a circuit has been closed through the "up"-setting magnet 75, core 76 of the "up"-restoring magnet 77, the conducting portion 78 of magnet 75 and out as shown by the arrows to the source of electro-motive-force 79, this has closed the switch 80 and the circuit through the lamp 47 of car B, which corresponds to the third floor. When, now, the car reaches the third floor and the gate 43 is opened, a circuit will be closed from the source of electro-motive-force 79 through the wire 81, through switch 82, arm 83 and stationary plate 84 of the circuit shifting switch, through the "up"-restoring magnet 77, and out to the other side of the source of electro-motive-force. This will raise the core 76 and break the circuit through the setting magnet 75 in the same way. If the "up" push-button 48 is pushed, it will obviously close the circuit through the "up" setting magnet 85 and light the lamp 45 in the car, and the parts will be restored to their normal condition when the gate 42 is opened, as this will energize the "up" restoring magnet 86 in the same manner.

"Down"-setting magnets 87 and 88 and re-string magnets 89, 90 for car B with corresponding stationary contact plates 91, 93, and contact plates 94, 95 and 96 corresponding to the similar plates 20, 22 and 23, are provided and the up-setting magnets 97, 98 and restoring magnets 99, 100 are provided for controlling the signals when the car A is going up.

As shown in Fig. 4, the restoring magnets

are in parallel so that if, for example, both cars are moving up and both lights for the fourth floor have been lighted, the opening of either gate 42 or 40 will energize both the up-restoring magnets for that floor and so restore both the corresponding signals to their normal condition.

It will be observed that each of the shifting switches normally limits the restoration to 10 that one or those push-button set mechanisms which correspond to the direction in which that particular car is moving, that is, if the car A, for example, is moving down, its circuit-shifting switch so controls its door switches that the opening of the gate 40 or 41 can only cause the energization of the "down" restoring magnets and will not affect the "up" restoring magnets, and vice versa if the car is moving up. In the embodiment shown each door switch is connected to a separate arm of the circuit-shifting switch and for each such arm an "up" and a "down" restoring contact is provided (such as 74 and 71 for the door switch 72) and each one of these contacts is connected through the corresponding magnets of that floor in parallel and to the corresponding stationary contact of the shifting switch of the other elevator, as shown in 30 Fig. 4.

It will also be observed that in the embodiment shown in the drawings there is only one wire running from each door switch and only one switch, that is a single wire at the gate, and this single wire and switch controls the restoration of the "up"-setting magnets for that floor, as well as for the "down"-setting magnets for that floor. This is preferably accomplished by providing a single switch having a single break or open point. This is a distinct improvement over, for example, the McLean Patents 748,408 and 748,409 as the wiring and switch construction is cut in half to accomplish the same results. The shifting switches which also control the restoring circuits are operated by the cars because they are thrown from their "up" to their "down" position, and vice versa by the cars as they reverse 45 their direction of movement wherever the cars may be in their shafts. The gate switches are, in the embodiment shown in the drawings, normally open, and this is 50 the preferable construction.

55 The passengers'-button-set device, which causes a signal to be given in the sense that the signals controlled by it cannot be given except when such device has been set, is shown in this embodiment of the invention 60 as a movable, weighted device such as indicated in Figs. 3 and 5, which is moved into its signal-giving position when the floor button is operated. It is preferably moved into position by a magnet, and is so shown. 65 When released the device automatically

moves back to its normal position, thus restoring the signal to normal condition. When it moves to its signal-giving condition, it calls into operation means which are adapted to hold it in such position that it 70 may maintain the signal after the floor-button has been operated, and this is preferably accomplished by the automatic closure of a maintaining circuit through a magnet. In the specific construction illustrated, when 75 the core 54 moves up to its signal-giving position, it calls into operation the maintaining circuit through the magnet 57, which holds the core, by closing the circuit through the normally-open switch at 61. I consider 80 it preferable to make the setting magnet also serve as a holding magnet, but do not limit myself to this construction.

If the passengers'-button-set device is held in its signal-giving position by a magnet as 85 in the specific construction illustrated, I provide suitable means to deenergize said magnet and release the same so that it will automatically move back to its normal position, 90 preferably by its own weight. Such deenergization is preferably accomplished or controlled by a normally-closed switch in the maintaining circuit which is opened at the proper time. In the embodiment illustrated in the drawings, such a switch is indicated at 58, 69' in Fig. 5, which is automatically opened when the corresponding floor gate or door switch 67 is operated. In the Smalley and Reiners 634,220 and the Collett 634,229 patents the restoring magnets are controlled by stationary contact plates corresponding to the floors and a moving brush which passes over them, such contact plates and brush being termed a "commutator." I prefer to energize the restoring magnets in succession by a form of commutator or circuit-selecting device in which the switch mechanism, instead of being stationary contacts which correspond to the floors as in the said patents, shall have 95 mechanism corresponding to each floor which are operated by the door gates. It will be obvious that there is corresponding to each floor a restoring magnet such as 59, and suitable switch mechanism for operating the same such as a door switch 67, and that, as such door switches may be closed in succession, they may accomplish the same 100 general result as the form of commutator illustrated in said prior patents, as both of 105 said patents, as well as my device, comprise switch mechanism corresponding to each floor for controlling the restoring magnets.

In order that the "down" restoring magnets, for example, may not be energized except when a car is going down, the rocking arm 19 which is operated automatically by the car, is provided. This serves to render the "up" restoring magnets operable only 115 when a car is moving up, and the "down" 120

restoring magnets operable only when a car is moving down. In the specific embodiment illustrated in the drawings it serves to connect the single door switch of any car with the up or the down restoring magnets corresponding to that floor.

I am aware that variations from the construction shown may be made without departing from the spirit of my invention as claimed, and I therefore do not desire to be limited to the particular construction shown in the drawings.

Having thus described my invention, I declare that what I claim as new and desire to secure by Letters Patent, is,—

1. In an elevator signaling apparatus in combination, a car, electrically-operated signaling means, means for operating the same comprising an "up" and a "down" passenger's button at each of several floors and mechanism corresponding to and set by each button, an electrically-operated restoring device for each button-set mechanism to cause the same to be restored to normal condition, a single electric switch corresponding to each floor, circuit-shifting switch mechanism having a shiftable portion in electric connection with said single switches and arranged to connect said switches with the "up"-restoring devices in one position and with the "down"-restoring devices in the other position, and means to automatically shift said shiftable portion correspondingly with the car's direction.

2. In an elevator signaling apparatus in combination, a pair of cars, electrically-operated signaling means corresponding to each car, means for operating the same comprising an "up" and a "down" passenger's button at each of several floors and mechanism corresponding to and set by each button, an electrically-operated restoring device for each button-set mechanism to cause the same to be restored to normal condition, a single electric switch corresponding to each floor for each car, circuit-shifting switch mechanism corresponding to each car and each having a shiftable portion, said shiftable portions being operable independently of each other and each in electric connection with those single switches which correspond to its car and arranged to connect said switches corresponding to that car with the "up"-restoring devices in one position and with the "down"-restoring devices in the other position, and means to automatically shift said portions independently of each other and correspondingly with the car's direction.

3. In an elevator signaling apparatus in combination, a car, electrically-operated signaling means, means for operating the same comprising an up and a down passenger's button at a floor and mechanism corresponding to and set by each button, an electric-

cally-controlled restoring means for each passenger's-button-set mechanism, a single normally open switch controllable by the car-operator and a circuit-shifting switch serving to connect said single normally-open switch with said restoring means alternately.

4. In an elevator signaling apparatus in combination, a car, electrically-operated signaling means, means for operating the same comprising an up and a down passenger's button at a floor and mechanism corresponding to and set by each button, an electrically-operated restoring means for each passenger's-button-set mechanism, a gate at the floor, a single normally open switch closed by said gate and a circuit-shifting switch serving to connect said normally open switch with said restoring means alternately.

5. In an elevator signaling apparatus in combination, a car, electrically-operated signaling means for signaling the car operator, means for operating the same comprising an "up" and "down" passenger's button at a floor, and mechanism corresponding to and set by each button, a gate at the floor, a single electric switch located at said floor and operable by the said gate, electrically-controlled restoring devices for each of said passenger's-button-set mechanisms and a circuit-shifting switch thrown by the car's movement and arranged to operatively connect said single floor switch with said restoring devices alternately.

6. In an elevator signaling apparatus in combination, a car, electrically-operated signaling means, means for operating the same comprising an "up" and a "down" passenger's button at each of several floors and mechanism corresponding to and set by each button, a single electric switch located at each floor and operable by the operator of the car, electrically-controlled restoring mechanism for the "up" and also for the "down" passenger's-button-set mechanisms, and a circuit-shifting switch thrown by the car's movement and arranged to operatively connect the said single switches with the "up"-restoring mechanism when the car is moving up and with the "down"-restoring mechanism when the car is moving down.

7. In an elevator signaling apparatus in combination, a car, electrically-operated signaling means for signaling the operator of the car, means for operating the same comprising an "up" and a "down" passenger's button at each of several floors and mechanism corresponding to and set by each button, a signal electric switch located at each floor and operable by the operator of the car, electrically-controlled restoring means for the "up" and also for the "down" passenger's-button-set mechanisms, and a

- 5 circuit-shifting switch thrown by the car's movement and arranged to operatively connect the said single switches with the "up" restoring mechanism when the car is moving up and with the "down" restoring mechanism when the car is moving down.
8. In an elevator signaling apparatus in combination, a car, electrically-operated signaling means, means for operating the same comprising an "up" and a "down" passenger's-button at each of several floors and mechanism corresponding to and set by each button, a gate at each floor, a single electric switch located at each floor and operated by its corresponding gate, electrically-controlled restoring mechanism for the "up" and also for the "down" passenger's-button-set mechanisms, and a circuit-shifting switch thrown by the car's movement and arranged to operatively connect the said single switches with the "up"-restoring mechanism when the car is moving up and with the "down" restoring mechanism when the car is moving down.
12. In an elevator signaling apparatus in combination, a pair of cars, electrically-operated signaling means for each car, means for operating the signals of both cars and comprising an "up" and a "down" passenger's-button at each of several floors and mechanism corresponding to and set by each button, a gate for each car at each floor, a single electric switch for each car located at each floor and operated by the corresponding gate, electrically-controlled restoring mechanism for all the "up" and also for all the "down" passenger's-button-set mechanisms, and a circuit-shifting switch for and operated by each gate, said switches being arranged in parallel, electrically-controlled restoring mechanism for the "up" and also for the "down" passenger's-button-set mechanisms, and a circuit-shifting switch thrown by the car's movement and arranged to operatively connect the said single switches with the "up"-restoring mechanism when the car is moving up and with the "down"-restoring mechanism when the car is moving down.
14. In an elevator signaling apparatus in combination, a pair of cars, electrically-operated signaling means for each car, means for operating the signals of both cars and comprising an "up" and a "down" passenger's-button at each of several floors and mechanism corresponding to and set by each button, a single electric switch for each car located at each floor and operable by the operators of the cars, electrically-controlled restoring mechanism for all the "up" and also for all the "down" passenger's-button-set mechanisms, and a circuit-shifting switch for each car controlled by that car's movement and each arranged to operatively connect the said single switches corresponding to that car with the "up"-restoring mechanism when that car is moving up and with the "down"-restoring mechanism when that car is moving down.
15. In an elevator signaling apparatus in combination, a pair of cars, electrically-operated signaling means for each car for signaling the operators, means for operating the signals of both cars and comprising an "up" and a "down" passenger's-button at each of several floors and mechanism corresponding to and set by each button, a single electric switch for each car located at each floor and operable by the operators of the cars, electrically-controlled restoring mechanism for all the "up" and also for all the "down" passenger's-button-set mechanisms, and a circuit-shifting switch for each car thrown by that car's movement and each arranged to operatively connect the said single switches corresponding to that car with the "up"-restoring mechanism when that car is moving up and with the "down"-restoring mechanism when that car is moving down.
16. In an elevator signaling apparatus in combination, a pair of cars, electrically-operated signaling means carried by each car, means for operating the signals of both cars and comprising an "up" and a "down" passenger's-button at each of several floors and mechanism corresponding to and set by each button, a gate at each floor for each car, a normally open single switch for each gate and closed by the operation of its corresponding gate, electrically-controlled restoring mechanism for all the "up" and also for all the "down" passenger's-button-set mechanisms, and a circuit-shifting switch for each car thrown by that car's movement and each arranged to operatively connect the said single switches corresponding to that car with the "up"-restoring mechanism when that car is moving up and with the "down"-restoring mechanism when that car is moving down.
17. In an elevator signaling apparatus in combination, electrically-operated signaling means, mechanism for operating the same comprising an "up" and a "down" passenger's-button at each floor, and mechanism for each button set by operation of the corresponding button, a gate at each floor,

restoring mechanism adapted to restore said passenger's-button-set mechanisms to normal condition and comprising a single normally-open restoring switch for each floor closed by operation of its corresponding gate, and a magnet corresponding to each passenger's-button-set mechanism and adapted to control the restoration of the same, and a circuit-shifting switch operated by the car's movement and automatically connecting said restoring switches with only those magnets corresponding to the "up"-passenger's-button-set mechanism when the car is moving up and vice versa.

15. 15. In an elevator signaling apparatus in combination, electrically-operated signaling means, mechanism for operating the same comprising an "up" and a "down" passenger's-button at each floor, and mechanism for each button set by operation of the corresponding button, a gate at each floor, restoring mechanism adapted to restore said passenger's-button-set mechanisms to normal condition, and comprising a single normally-open restoring switch for each floor closed by operation of its corresponding gate, and a magnet corresponding to each passenger's-button-set mechanism and adapted to control the restoration of the same, and a circuit-shifting switch operated by the car's movement and automatically connecting said restoring switches with only those magnets corresponding to the "up" passenger's-button-set mechanism when the car is moving up and vice versa, said restoring switches being arranged so that the closure of one of said switches will not restore the passenger's-button-set mechanism of any other floor.

40. 16. In an elevator signaling apparatus in combination, electrically-operated signaling means, mechanism for operating the same comprising an "up" and a "down" passenger's-button at each floor and mechanism for each button set by operation of the corresponding button, a gate at each floor, restoring mechanism adapted to restore said passenger's-button-set mechanisms to normal condition and comprising a single normally-open restoring switch for each floor closed by operation of its corresponding gate, and a restoring magnet corresponding to each passenger's-button-set mechanism to restore the same to normal condition, and a circuit-shifting switch operated by the car's movement and automatically connecting said restoring switches with only those magnets corresponding to the "up" passenger's-button-set mechanisms when the car is moving up and vice versa.

65. 17. In an elevator signaling apparatus in combination, a car, signaling means, a movable weighted device and connections adapted to cause a signal to be given when said weighted device is moved against the force

of said weight, means to so move the same comprising an electro-magnet and a switch in a circuit thereto operable by a passenger on a floor, means called into operation by the movement of said weighted device and 70 adapted to control the electro-magnet to cause it to hold said device in such position that it will maintain the signal after said passenger's switch has opened its circuit to said magnet, means to release said weighted 75 device and allow it to fall and thereby discontinue the signal and comprising a restoring electro-magnet and switch mechanism corresponding to said floor for operating said magnet.

18. In an elevator signaling apparatus in combination, a car, signaling means carried by the car; and for each floor a movable weighted device and connections adapted to cause a signal to be given when said 85 weighted device is moved against the force of said weight, means to so move the same comprising an electro-magnet and a normally-open switch in a circuit thereto openable and closable at all times by a passenger 90 on that floor, means called into operation by the movement of said weighted device and adapted to control the electro-magnet to cause it to hold said device in such position that it will maintain the signal after said 95 passenger's switch has opened its circuit to said magnet; and means for independently operating said magnets to release said weighted devices and allow them to fall and thereby discontinue the signal and comprising 100 a restoring electro-magnet for each floor and switch mechanism corresponding to each floor, said means being controlled by the direction of movement of the car.

19. In an elevator signaling apparatus in 105 combination, a car, a signal corresponding to each floor for the operator of the car; and for each floor a movable weighted device and connections adapted to cause a signal to be given when said weighted device 110 is moved against the force of said weight, means to so move the same comprising an electro-magnet and a switch in a circuit thereto operable by a passenger on that floor, means called into operation by the 115 movement of said weighted device and adapted to control the electro-magnet to cause it to hold said device in such position that it will maintain the signal after said passenger's switch has opened its circuit to 120 said magnet; means to release said weighted devices and allow them to fall and thereby discontinue the signal and comprising a restoring electro-magnet for each floor and switch mechanism corresponding to each 125 floor for independently operating said magnets, and means operated by the car and rendering said restoring magnets operable during only one direction of movement of 130 the car.

20. In an elevator signaling apparatus in combination, a car, a signal, a signal-setting device movable into position to cause a signal to be given and automatically movable into non-signal-giving position, means controlling the movement of the same into signal-giving position comprising a normally-open passenger's switch closable and openable by a passenger on a floor; an electro-magnet adapted to hold said signal-setting device in its signal-giving position, a normally-open maintaining circuit around said passenger's switch and through said magnet and closed automatically when said signal-setting device is moved to its signal-giving position, a normally-closed restoring switch corresponding to said floor also in the maintaining circuit and operating to break the maintaining circuit, and a circuit-shifting means controlled by the car for rendering said latter switch operable during only one direction of movement of the car. 70
21. In an elevator signaling apparatus in combination, a car, signaling means, a signal-controlling device movable into such position that a signal may be given, means controlling the movement of the same comprising a passenger's-button on a floor; an electro-magnet adapted to hold said device in its signal-giving position, a normally-open maintaining circuit through said magnet closed automatically when said signal-controlling device is so moved, restoring means to deenergize said magnet and release said device and comprising mechanism corresponding to said floor and car and located outside the car; and circuit-shifting means operated automatically by the car and serving to render said restoring means capable of breaking said maintaining circuit during only one direction of movement of the car. 75
22. In an elevator signaling apparatus in combination, a car, signaling means, a signal-controlling device movable into such position that a signal may be given, means controlling the movement of the same comprising a passenger's-button on a floor; an electro-magnet adapted to hold said device in its signal-giving position, a normally-open maintaining circuit through said magnet closed automatically whenever said signal-controlling device is so moved, restoring means to deenergize said magnet and release said device and comprising a restoring electro-magnet, a switch in said maintaining circuit operable by said magnet, and means corresponding to said floor for operating said magnet. 80
23. In an elevator signaling apparatus in combination, a car, signaling means, a signal-controlling device movable into such position that a signal may be given, means controlling the movement of the same comprising a passenger's-button on a floor; an electro-magnet adapted to hold said device in its signal-giving position, a normally-open maintaining circuit through said magnet closed automatically when said signal-controlling device is so moved, restoring means to deenergize said magnet and release said device and comprising a restoring electro-magnet, a normally-closed switch in said maintaining circuit opened by said magnet, and a normally-open switch corresponding to said floor for operating said magnet. 85
24. In an elevator signaling apparatus in combination, a car, a signal and a normally-open circuit thereto, a signal-controlling device movable into position to close said circuit and automatically movable into position to open the same when released, means controlling the movement of the same into signal-setting position comprising a passenger's-button on a floor; an electro-magnet adapted when energized to hold said signal-controlling device in its signal-giving position, a normally-open maintaining circuit through said magnet closed automatically when said signal-setting device is so moved, restoring means to deenergize said magnet and release said device and comprising a restoring electro-magnet, a normally-closed switch in said maintaining circuit opened by said magnet, a normally-open switch corresponding to said floor outside the car and independent of said signal and first magnet for energizing said restoring magnet, and a switch operated by the car for cutting out said restoring magnet when the car moves in one direction. 90
25. In an elevator signaling apparatus in combination, a car, signaling means for each floor for the car-operator; and corresponding to each floor and each direction of movement of the car a signal-controlling device movable into such position that a signal may be given, means controlling the movement of the same comprising a passenger's-button on a floor, an electro-magnet adapted to hold said device in its signal-giving position, a normally-open maintaining circuit through said magnet closed automatically when said signal-controlling device is so moved, restoring means to deenergize said magnet and release said device and comprising mechanism corresponding to said floor located outside the car; and means operated automatically by the car and serving to render only those magnets deenergizable which correspond to the direction the car is moving. 95
26. In an elevator signaling apparatus in combination, two cars, signaling means for each car, signal-controlling mechanism movable into such position that a signal may be given for each car, electro-magnetic means adapted to hold said signal-controlling mechanism in the signal-giving position, means for maintaining said electro-magnetic means energized comprising a suitable circuit and normally-open switch mechanism 100

- 130

therein closed automatically when said signal-controlling mechanism is moved to its signal-giving position, restoring means adapted to restore the parts to normal condition and comprising electro-magnetically-operated mechanism adapted to break said maintaining circuit and a controlling switch therefor corresponding to each car, and mechanism for each car automatically operated by that car and serving to render the said controlling switch of that car incapable of operating said restoring means during one direction of movement of that car.

27. In an elevator signaling apparatus in combination, a car, an "up" and a "down" signal-controlling device corresponding to a floor and movable into such position that a signal may be given, means controlling the movement of the same comprising an "up" and a "down" normally-open passenger's switch operable from said floor; an electro-magnet for each of said signal-controlling devices adapted to hold said device in its signal-giving position, a maintaining circuit for each magnet around the corresponding passenger's-button, a normally-open switch in each circuit automatically closed when its signal-controlling device is so moved, a normally-closed switch in each maintaining circuit and a magnet for opening each switch, a door-operated switch mechanism, and a switch operated automatically by the car and arranged to render one of said latter magnets operative by said door switch 35 when the car is moving up and the other when the car is moving down.

28. In an elevator signaling apparatus in combination, two cars, a signal corresponding to each car, up signal-controlling mechanism movable into position such that both said signals may be given simultaneously and automatically movable into non-signal-giving position, electro-magnetic means adapted to hold said signal-controlling mechanism in the signal-giving position and having maintaining circuit connections therefor closed automatically whenever said signal-setting mechanism is moved to the signal-giving position, and switch mechanism for each car adapted independently to break said maintaining circuit connections and restore both said signals to normal condition after having been given, and means for each car operated automatically by that car and rendering its said switch mechanism incapable of restoring said up signal-controlling mechanism when said car is moving down, and circuits for operating the signals in parallel with the maintaining circuits.

29. In an elevator signaling apparatus in combination, a car, a passenger's-button on a floor, a signal-controlling device controlled thereby and movable into signal-giving position, a signal operated whenever said signal-

controlling device is so moved, a holding magnet and a normally-open maintaining circuit closed automatically when said signal-controlling device is set, and means for de-energizing the magnet but operable during only one direction of movement of the car. 70

30. In an elevator signaling apparatus in combination, a car, a signal, a signal-controlling device movable into such position that a signal may be given, means controlling the movement of said device and comprising a passenger's-button on a floor; an electro-magnet adapted to hold said device in its signal-giving position, a normally-open maintaining circuit through said magnet closed automatically when said passenger's-button is operated, deenergizing means for said magnet comprising mechanism corresponding to that floor and car, and a directional device automatically rendering said deenergizing means inoperative during one direction of movement of the car, said maintaining circuit being independent of said directional device. 75 80 85

31. In an elevator signal apparatus in combination, a car, a signal, a signal-controlling device movable into such position that a signal may be given, means controlling the movement of said device comprising a passenger's-button on a floor; an electro-magnet adapted to hold said device in its signal-giving position, a normally-open maintaining circuit through said magnet closed automatically whenever said passenger's-button is operated and said signal controlling device is so moved, deenergizing means for said magnet comprising an electric circuit and a normally-open switch therein, and a directional device operated automatically by the car and serving to render said deenergizing circuit inoperative during one direction of movement of the car, said maintaining circuit being independent of said directional device. 90 95 100 105

32. In an elevator signaling apparatus in combination, a car, signaling means; and corresponding to each direction of movement of the car a signal-controlling device movable into such position that a signal may be given, means controlling the movement of said device and comprising a passenger's-button at a floor, an electro-magnet adapted to hold said device in its signal-giving position, a normally-open maintaining circuit through said magnet closed automatically 110 when said passenger's-button is operated; and, for each magnet, means causing the de-energization thereof; a common switch controlling both magnets, and a directional switch operated by the movement of the car 115 120 125 and rendering said common switch capable of controlling only one of said magnets at a time.

33. In an elevator signaling apparatus in combination, a car, signaling means; and 130

corresponding to each direction of movement of the car a signal-controlling device movable into such position that a signal may be given, means controlling the movement 5 of said device and comprising a passenger's button at a floor, an electro-magnet adapted to hold said device in its signal-giving position, a normally-open maintaining circuit through said magnet closed automatically 10 when said passenger's-button is operated; and, for each magnet, means causing the de-energization thereof; a common switch controlling both magnets and controllable by the car-operator as to its time of operation, 15 and a directional switch operated by the movement of the car and rendering said common switch capable of controlling only one of said magnets at a time.

34. In an elevator signaling apparatus in combination, a car, electrically-operated signaling means, means controlling the same and comprising an up and a down passenger's-button at a floor and a device corresponding to and set by each button, a holding magnet for each device having a normally open maintaining circuit there-through closed when its button is operated, means for de-energizing said magnets and comprising a circuit for and controlling each 25 magnet whereby each may be de-energized independently of the other, a switch normally open while the car is in motion and controllable by the operator of the car, and a circuit-shifting switch and connections 30 whereby said first switch is connected to said de-energizing circuits alternately.

35. In an elevator signaling apparatus in combination, a car, an electrically-operated signal and a circuit therefor; and corresponding to each floor a signal-controlling device movable into such position that a signal may be given, means controlling the movement of said device and comprising a passenger's-button on a floor, a magnet 40 adapted to hold said device in its signal-giving position, a normally open maintaining circuit through said magnet closed whenever said passenger's-button is operated and said signal controlling device is so moved, 45 said maintaining circuit being in parallel with said signal circuit; means whereby said magnets may be de-energized in succession during the trip of the car in one direction, and a directional device operated by the 50 car and preventing the de-energization of said magnets while the car is traveling in the opposite direction.

36. In an elevator signaling apparatus in combination, a car, a signal, a signal-setting device movable into position to cause a signal to be given and automatically movable into non-signal-giving position, means controlling the movement of said device into signal-giving position comprising a 60 normally open passenger's-switch closable and

openable by a passenger on a floor; an electro-magnet adapted to hold said signal-setting device in its signal-giving position, a normally-open maintaining circuit around said passenger's-switch and through said 70 magnet and closed automatically whenever said passenger's-switch is operated and said signal device is so moved, and means for de-energizing said magnet as the car passes the floor in the direction corresponding to 75 the passenger's-button.

37. In an elevator signaling apparatus in combination, a car, a signal, a signal-setting device movable into position to cause a signal to be given and automatically movable 80 into non-signal-giving position, means controlling the movement of said device into signal-giving position comprising a normally open passenger's-switch on a floor; an electro-magnet adapted to hold said signal-setting device in its signal-giving position, said magnet being in circuit with said passenger's-switch, a normally-open maintaining circuit through said magnet and around said switch closed automatically 85 whenever said passenger's switch is operated and said signal-setting device is so moved and means for de-energizing said magnet as the car passes the floor in the direction corresponding to the passenger's-button. 95

38. In an elevator signaling apparatus in combination, a car, a single signaling device for each floor, each adapted to cause a signal to be given in each direction of movement of the car; and means for operating 100 the same in each direction of movement of the car and comprising an "up" and a "down" passenger's-button at each floor, mechanism for and independently set by each button, and a switch thrown by that car and co-operating with the up and down passenger's-button-set mechanisms alternately to control the signals. 105

39. In an elevator signaling apparatus in combination, a car, a single signal lamp for 110 each floor, each adapted to cause a signal to be given in each direction of movement of the car; means for operating the same in each direction of movement of the car and comprising an "up" and a "down" 115 passenger's-button at each floor, mechanism for and independently set by each button, and a switch thrown by that car and co-operating with the up and down passenger's-button-set mechanisms alternately to control 120 the signals.

40. In an elevator signaling apparatus in combination, a car, a signal, a signal-controlling device movable into position such that a signal may be given, means for so moving and holding the same comprising a passenger's-button on a floor and a holding magnet, electro-magnetic mechanism operating to restore said signal-controlling device, and a circuit-shifting device operated 125 130

- by the car and rendering said electro-magnetic mechanism operable during only one direction of movement of the car.
41. In an elevator signaling apparatus in combination, two cars, a signal for each car, a signal-controlling device movable in position such that a signal may be given, means for so moving and holding the same comprising a passenger's-button on a floor and a holding magnet, electro-magnetic mechanism to restore said signal-controlling device, and a circuit-shifting device for each car operated by that car and rendering said electro-magnetic mechanism operable during only one direction of movement of a car.
42. In an elevator signaling apparatus in combination, a car, signaling means and a circuit therefor, a signal-controlling device movable into such position that a signal may be given, means controlling the movement of the same comprising a passenger's-button on a floor; an electro-magnet adapted to hold said device in its signal-giving position, a normally-open maintaining circuit through said magnet in parallel with said signaling circuit and closed automatically when said signal-controlling device is so moved, restoring means to deenergize said magnet and release said device and comprising mechanism corresponding to said floor and car and located outside the car; and circuit-shifting means operated automatically by
- the car and serving to render said restoring means capable of breaking said maintaining circuit during only one direction of movement of the car.
43. In an elevator signaling apparatus in combination, a car, signaling means, a signal-controlling device movable into such position that a signal may be given, means controlling the movement of the same comprising a passenger's-button on a floor and an electro-magnet energized through the operation of said button, said electro-magnet also adapted to hold said device in its signal-giving position, a normally-open maintaining circuit through said magnet closed automatically when said signal-controlling device is so moved, restoring means to deenergize said magnet and release said device and comprising a restoring electro-magnet, a normally-closed switch in said maintaining circuit opened by said magnet, a normally-open switch corresponding to said floor and car for operating said magnet, another car, and a normally-open switch corresponding to said floor and other car and also adapted to operate said magnet.

In testimony whereof I affix my signature, in presence of two witnesses.

FRED S. PAYNE.

Witnesses:

JULIAN S. WOOSTER,
GEO. A. HOFFMAN.

It is hereby certified that in Letters Patent No. 1,108,782, granted August 25, 1914, upon the application of Fred S. Payne, of Boston, Massachusetts, for an improvement in "Electric Signaling Devices for Elevators," errors appear in the printed specification requiring correction as follows: Page 1, line 40, for the word "connection" read *connections*; page 2, line 122, for the compound word "re-string" read *restoring*; page 3, line 57, for the word "signals" read *signal*; page 4, line 90, before the word "down" insert the article *a*; page 6, line 13, for the word "mechanism" read *mechanisms*; page 9, line 27, for the word "when" read *whenever*; same page, line 73, before the word "device" insert the word *setting*; and that the said Letters Patent should be read with these corrections therein that the same may conform to the record of the case in the Patent Office.

Signed and sealed this 22nd day of September, A. D., 1914.

[SEAL.]

R. F. WHITEHEAD,
Acting Commissioner of Patents.

Correction in Letters Patent No. 1,108,782.

It is hereby certified that in Letters Patent No. 1,108,782, granted August 25, 1914, upon the application of Fred S. Payne, of Boston, Massachusetts, for an improvement in "Electric Signaling Devices for Elevators," an error appears in the printed specification requiring correction as follows: Page 4, line 126, for the word "signal" read *single*; and that the said Letters Patent should be read with this correction therein that the same may conform to the record of the case in the Patent Office.

Signed and sealed this 24th day of November, A. D., 1914.

[SEAL.]

R. F. WHITEHEAD,
Acting Commissioner of Patents.
